UNITED STATES PATENT OFFICE.

ISAAC J. KILBURN, OF DENVER, COLORADO, ASSIGNOR TO THE AMERICAN SWITCH POINT PROTECTOR AND RAILROAD EQUIPMENT COMPANY, OF DENVER, COLORADO, A CORPORATION OF COLORADO.

SWITCH-POINT PROTECTOR.

Application filed March 26, 1928. Serial No. 264,631.

This invention relates to protectors for points of railway switches and its main object is to provide a simple device that is readily attached to the pivoted points of a switch 5 without fastening means other than those used for securing the points together, and which will protect the ends of the points against wear by preventing their contact with the flanges of wheels on cars passing 10 through the switch.

It is well known that the points of railway switches wear soonest at their tapered end portions at which they engage the rails of the track, and that the life of a switch 15 point is for that reason comparatively short.

The renewal of switch points involves considerable labor and expense, and by the use of my protector, which may be produced at comparatively low cost and which can be renewed by the mere expedient of loosening and re-applying two or three nuts of the switch, much time, labor and expense is saved.

An embodiment of the invention has been 25 illustrated in the accompanying drawings, in the several views of which like parts are similarly designated, and in which,

Figure 1 represents a plan view of a portion of a railway switch, showing the protectors in their operative position on the 30 points of the switch,

Figure 2, a fragmentary cross-section taken on the line 2—2, Figure 1, and drawn to an enlarged scale,

Figure 3, an enlarged side-view of the end-portion of one of the switch-points with the protector in place, looking in the direction of the arrow A in Figure 2,

Figure 4, a further enlarged section 40 through the protector, apart from the switch tongue, on the line 4—4, Figure 3, and

Figure 5, a plan view of the protector in its position against the respective switch-point.

Referring further to the drawings, the numerals 5 designate the tapering points of a railway switch connected as usual by rods 6.

The so-called number one rod 6 is fastened to the points through the intermediary of 50 lugs or brackets 7 that are secured to the points by means of bolts 8 at opposite sides of a web 9, and that are fastened to the rods by the use of bolts 10.

The bolts 8 are, in the present instance,

utilized to also secure the protector on the 55 respective switch-point, as will now be described.

The protector consists of a bar 12 having, at one end, an inturned head 13 which, in practise, engages the free end of the switch-point 5, and which, at its opposite end, is tapered to a sharp edge to facilitate the movement of the car-wheel-flanges from the point onto the protector.

The bar is curved transversely and it has 65 intermediate of its end-portions, a flange 14 for its attachment to the point. The flange is laterally offset to form a recess for the reception of the upper portion of the lug by which the respective switch-point is fastened to the 70 rod, and the lower edge of the flange is concaved to escape the web of the lug.

The flange has, furthermore, two or three holes adapted to register with the bolts 8, by which the lug 7 is attached to the point, thereby permitting of fastening the protector to the switch-point by the nuts 15 on the ends of the bolts which ordinarily secure the lug.

The protector thus secured in its operative position, lies flat against the tread of 80 the switch-point and embraces the upper portion of the respective lug, as best shown in Figure 2. Its head, adjacent the free end of the point, abuts against said end and not only protects the end against wear, but, furthermore, relieves the bolts by which the protector is fastened to the point, from stress.

The opposite tapering end of the protector merges to the surface of the point so as to provide a smooth approach for the flanges of 85 the car wheels from the surface of the point onto that of the protector.

It will thus be apparent that the end-portions of the switch-points are adequately protected against wear by contact of the flanges 90 on the car-wheels, that the protector is easily applied and as readily detached and replaced in case of wear or breakage, and that no fastening devices are required other than the bolts already in use on switches to secure 100 the points thereof to the rods.

What I claim and desire to secure by Letters Patent is:

1. The combination with a railway switch including a point, a rod, and a webbed lug on the rod, fastened to the point by bolts, of a protector engaging along an end-portion of the point, embracing the lug exclusive of its

web, and held in place by the bolts of the lug.

2. The combination with a switch-point, of a protector bolted to the point and engaging along an end-portion of the same, the protector having a head abutting against the end of the point, and the end of the protector opposite to the head, tapering to the surface of the point.

3. A protector for a switch-point, comprising a bar provided with a recessed and apertured flange for its attachment to the point and having at one end, a head for engagement with the free end of the point, the opposite end of the bar being tapered to merge toward the surface of the point.

4. In a railway switch, a switch rail of standard construction, and a protective plate fastened upon the outside of the rail and having a wear-edge extending adjacent to and along the tread-surface of the rail to be engaged by flanged wheels moving upon the rail.

5. In a railway switch, a switch rail of standard construction, and a protective plate fastened upon the outside of the rail and hav-

ing a wear-edge extending adjacent to and along the tread-surface of the rail and beyond the free end of the same, to be engaged by flanged wheels moving upon the rail.

6. In a railway switch, a switch rail of standard construction, and a protective plate fastened upon the outside of the rail and having a wear-edge extending adjacent to and along the tread-surface of the rail, to be engaged by flanged wheels moving upon the rail, the end of the protector opposite to that adjacent the free end of the rail merging to the surface of the rail.

7. In a railway switch, a switch rail of standard construction, a bracket for the coupling rod of the switch, and a protector comprising a plate extending along the tread-portion of the rail and fastened upon the outside of the switch rail with respect to the stock-rail with which it cooperates, over and around the bracket.

In testimony whereof I have affixed my signature.

ISAAC J. KILBURN.
